UNITED STATES PATENT OFFICE

GEORGE R. LIPPITT, OF CLEVELAND, OHIO, ASSIGNOR TO THE BISHOP & BABCOCK MFG. COMPANY, OF CLEVELAND, OHIO, A CORPORATION OF OHIO

DESIGN FOR A SODA FOUNTAIN

Application filed August 27, 1931. Serial No. 40,939. Term of patent 7 years.

To all whom it may concern:

Be it known that I, GEORGE R. LIPPITT, a citizen of the United States, residing at Cleveland, in the county of Cuyahoga, State of Ohio, have invented a new, original, and ornamental Design for Soda Fountains, of which the following is a specification, reference being had to the accompanying drawing, forming a part thereof, in which the figure is a front perspective view of a soda fountain showing my new design.

I claim:

The ornamental design for a soda fountain as shown.

In testimony whereof, I hereunto affix my signature this 22 day of August, 1931.

GEORGE R. LIPPITT.
